[57] CLAIM

The ornamental design for tea kettle, as shown.

DESCRIPTION

FIG. 1 is a perspective view of the invention;

FIG. 2 is a side elevational view of the invention shown
in FIG. 1;

FIG. 3 is a front elevational view of the invention;

FIG. 4 is a rear elevational view of the invention;

FIG. 5 is a top plan view of the invention shown in
FIG. 1; and,

FIG. 6 is a bottom plan view of the invention shown in
FIG. 1.

FIG. 1

FIG. 2

FIG. 3

FIG. 4

FIG. 5

FIG. 6
